UNITED STATES PATENT OFFICE.

WILLIAM S. MACHARG, OF CHICAGO, ILLINOIS.

TUBBING FOR TUNNELING DEVICES.

SPECIFICATION forming part of Letters Patent No. 673,852, dated May 7, 1901.

Application filed September 3, 1900. Serial No. 28,858. (No model.)

To all whom it may concern:

Be it known that I, WILLIAM S. MACHARG, a citizen of the United States, residing at Chicago, in the county of Cook and State of Illinois, have invented a certain new and useful Improvement in Tubbing for Tunneling Devices, of which the following is a specification.

My invention relates to tubing for use in tunneling-work.

10 My improvements are illustrated in the accompanying drawings, wherein—

Figure 1 is a longitudinal section through a portion of the tubing with the masonry shown inside and the shield outside. Fig. 2 15 is a cross-section through a portion of the tubing. Fig. 3 is a detail of the wedge-shaped key. Fig. 4 is a detail of the wedging-blocks.

Like parts are indicated by the same letters 20 in all the figures.

A indicates the masonry.

B B are sections of wood, preferably approximately eight inches square in cross-section and about two feet long. Each of these 25 sections is grooved to receive a tongue C. D is a slot in the end of each of these sections, and there is one such slot in each end. Into these slots is received a hoop or band E. F F are somewhat similar blocks in a similar way 30 grooved and slotted, but of different size and having inclined opposed faces, so that they can be driven in to tighten the sections of tubing as they are put into place. These wedge-shaped portions would be put in at 35 such points as to come opposite the heads of the jacks, so that as the parts are put together the first action of the head of the jacks is to force them into position, so as to tighten the blocks which form the sections of tubing. H H are wedge-shaped blocks, which 40 together form the wedge-shaped key-block, and they are similarly grooved and slotted. It will be understood that the size, proportion, and exact shapes of these several blocks, 45 together with their grooves and slots, may be varied to suit convenience. The several blocks may be tongued and grooved together, if thought necessary.

It is not necessary here to go into a detailed description of the method of tunneling 50 to which my improvements apply; but it will

be understood that there is an outer shield, which is moved forward as the work is done, that the masonry is built inside the tubing, and that as the excavation proceeds the tubing is extended by building new sections thereon in the excavated cavity. The blocks, shaped as shown, are built up into the circle or annulus, being properly supported and held together by the tongues or hoops, or 55 both. The several wedge blocks and keys are driven into position by the jacks, thus forcing all the parts into position, so as to form a tight and permanent annulus. The hoop is then let into the slot on the exposed 60 ends just as the inner hoop had been previously received into the inner ends of the tubing-sections as they were brought together. Then when the masonry has been extended the next section of tubing can be 65 put up in the same way.

The key-block is arranged in sections which can be placed into position, the last being driven home by the jack.

I claim—

1. A tubing for tunneling purposes comprising a series of tubing annular sections, the adjacent sections slotted to receive one and the same hoop, and each such section consisting of section-blocks longitudinally 75 tongued and grooved together.

2. In a tubing for tunneling purposes, a series of annular sections joined together end to end and comprising each a series of short blocks tongued and grooved at their meeting 80 edges, and wedge-blocks associated therewith, adapted to tighten the short blocks in the annular sections of tubing.

3. In a tubing for tunneling purposes, a series of annular sections suitably joined together end to end, and comprising each a series of short blocks tongued and grooved at their meeting edges, and wedge-blocks associated therewith, adapted to tighten the short blocks in the annular section of tubing, and 85 one of said blocks consisting of a series of short sections which can be successively placed in position.

WILLIAM S. MACHARG.
